WHEEL TRUING DEVICE

Rufus W. Fuller, Deerfield, Mass., assignor to
Production Machine Company, Greenfield,
Mass., a corporation of Massachusetts

Application August 24, 1935, Serial No. 37,703

5 Claims. (Cl. 125—11)

The present invention relates to a wheel truing device for grinding and polishing wheels and is designed more particularly for use on that type of machine in which the space available for the truing device is restricted as, for example, in certain types of machines employing a belt feed for rotating and feeding the work.

It is an object of the invention to provide a truing device which may be permanently attached to the machine, but which will be completely out of the way of the operator or the work when not in use.

It is a further object to provide a construction which permits the device to be positively and rigidly locked in position when the truing operation is being performed, thus eliminating any chattering of the tool and thereby securing a more uniform and exact wheel surface.

A further object of the invention is to provide a construction which will in no way interfere with the changing of wheels either to a different size or to a different type or material, and in which various types of tools may be used interchangeably, so that the same truing device may be used to dress any grinding or polishing wheel with which the machine is or may be equipped.

In the drawings illustrating the preferred embodiment of the invention, Fig. 1 shows in full lines a side elevation of the truing device in operative position on the wheel casing, the dotted lines representing the device thrown back on the casing in inoperative position; Fig. 2 is an end view of the device; Fig. 3 is a side elevation, on a reduced scale, of a polishing machine of well-known manufacture, with the truing device on the wheel casing, showing the mechanism for moving the wheel toward and away from the truing device; Fig. 4 is a perspective view of the tool holder with a tool or stick of abrasive material, the several parts being aligned but separated in order to illustrate more clearly their construction and relation; Fig. 5 is a side elevation showing a tool holder for holding a knife for trimming cloth polishing wheels; Fig. 6 is a plan view of the knife used in the holder of Fig. 5; Fig. 7 is a side elevation of a tool holder and tool for raking out cloth wheels; and Fig. 8 is an end view of the same.

The truing device comprises, generally speaking, a tool-holding arm pivotally mounted upon the hood or other fixed portion of the machine. When not in use the arm and holder will be tipped or swung back out of the way. When in use the arm and tool are positioned by means of a fixed abutment against which a contacting

face on the arm is rigidly clamped. Suitable adjusting and feeding devices are provided for bringing the tool and wheel surface in proper relative position and causing the tool to operate across the face of the wheel.

The truing device of the drawings comprises an arm 11 pivotally mounted on the hood or casting 13 for the polishing wheel 15 by means of stub shaft 17 carried by lugs 19 which may be formed as an integral part of the wheel hood. The hood also has an abutment 21 with a threaded stud 23 projecting from the face thereof. When the truing device is in operative position, a contact face on the arm bears against the abutment. The arm is held rigidly against the abutment by means of an internally threaded sleeve 25 formed on the lower end of the spindle 27 which is slidably and rotatably mounted in the arm 11. A hand grip or wheel 29 on the upper end of the spindle affords a convenient means for rotating the spindle and sleeve to clamp the arm fixedly in position. Slidably mounted on the transverse guideway 31 at the front or free end of the arm 11 is the tool holding carriage 33. This is moved along the guideway to feed the tool across the face of the grinding or polishing wheel by means of the feed screw 34 and hand wheel 35.

Secured in an inclined, transverse bore in the carriage by the clamping bolts 36 is the cylindrical shank 37 of the tool holder mounting or post 39 which in turn is provided with a bore and clamping bolt 41 for the tool holder proper.

As shown in Figs. 4, 5, 7, and 8, the holder comprises a cylindrical member 43 adapted to be secured in the bore of the mounting or post 39 and tool holding or clamping means of a form adapted to the particular type of tool employed. Thus in the ordinary type of wooden wheel with abrasive coating where a stick of abrasive material such as carborundum is to be used for truing the wheel, the holder will be as shown in Fig. 4 wherein the cylindrical member 43 is provided with an abutment piece 45 having the shoulder 47 to engage the face of the abrasive stick 49, a cap piece or clamping member 51 being tightly clamped against the other two faces of the stick by the clamping bolt 53 which passes through slot 55 in the cap piece and enters the threaded hole 57 in the abutment member. The cap piece is formed with the clamping faces 59 and shoulders 61 for engagement with the stick 49 and also has the triangular boss or extension 63 to contact with the face of the abutment piece 45 so that when the parts are clamped together, a

firmer contact and more even distribution of pressure will result and there will be less liability of fracture of the stick.

The bodily movement of the wheel 15 within the hood 13 to bring the wheel into proper engagement with the truing tool is obtained by mounting the wheel shaft 65 in bearings in the upper end of lever 67 pivoted at 69 and having the downwardly and forwardly inclined extension or arm 71. By means of the hand wheel 73 and the screw shaft 75 suitably connected to the end of the extension, the lever 67 may be adjusted about its pivot 69 to the desired position for the proper operation of the truing tools or devices.

The main driving pulley 77 being co-axial with the pivot of the wheel carrying lever, the tension of the driving belt 79 is unaffected by such adjusting movement of lever and wheel. A belt 20 tightener comprising the idler pulley 81 mounted on arm 83 also pivoted at 69 with slot 85 and bolt 87 affords means for adjusting the driving belt tension.

For trimming cloth wheels, the holder illustrated in Fig. 5 is used with a round nose knife 89, as shown in Fig. 6, which is retained in the slot 91 by set screws 93.

After a cloth wheel has been used for some time, it becomes matted down. To rake out the 30 wheel so that it may be made serviceable for further use, it is customary to use a wooden stick with protruding nails, held in the hand of the operator. The holder and tool of Figs. 7 and 8 are adapted to rake out cloth wheels, eliminating the danger present when a hand-held rake is used. U-shaped teeth 95 are inserted in holes in the extension 97 on the holder, and held securely by set screws 99.

The operation of the truing device when applied to a machine of the type shown in the drawings, is as follows:

In normal operation of the machine, i. e., when it is grinding or polishing the work presented to it, the truing device will be swung or tipped backwardly into the position shown in dotted outline in Fig. 1, where it can in no way interfere with the view or manipulations of the operator or the grinding operation of the machine.

When it is desired to true the grinding or polishing wheel, the truing device will be tipped forwardly, until its contact face engages the abutment 21, and the threaded socket 25 on the spindle 27 registers with the fixed threaded stud 23 projecting from the abutment 21 on wheel 50 hood, the spindle being raised at this time in its bearing in the arm 11. On rotation of the hand wheel 29, the threaded socket 25 will be screwed down on the stud 23 until the arm 11 carrying the trueing device is held firmly and rigidly 55 against the abutment 21.

The proper tool or instrumentalities being mounted in the tool holder, as for example, the abrasive stick 49, the tool holder support or post 39 and the tool holding member 43 will be adjusted in their respective bores or sockets to bring the abrasive stick into proper position, the parts being secured by the tightening of the clamping bolts 36 and 41.

In order to bring the polishing wheel and truing tool into proper relative position, the wheel will be adjusted forwardly or backwardly, as the case may be, by means of the screw shaft 75 and hand wheel 73, thereby swinging the wheel support lever 67 about its pivot 69 to bring the

surface of the wheel into proper operative relation to the truing tool.

The truing operation is performed with the polishing wheel rotating, the truing tool being fed across the face of the wheel by means of the feed screw 34 and hand wheel 35. If more than one travel or cut of the truing wheel is required, the polishing wheel can be easily and accurately adjusted for subsequent cutting by turning the hand wheel 73 of the screw shaft 75.

After the truing of the wheel has been completed, the truing device will be released by reversing the rotation of the threaded sleeve and spindle 25 and 27, and the whole device turned backwardly into its original dotted line position in Fig. 1.

When the knife or rake is used in place of the abrasive stick the manipulations and operations will be exactly the same except as to the character of the truing action of the tool, the uneven surface of the cloth or felt wheel being cut away by the round nose knife 89 and the matted or hardened surface of the cloth wheel being loosened up by the rake teeth 95.

While it is not essential that the particular form of tool holder illustrated in Fig. 4 be used, this has been found most satisfactory in actual use, the arrangement of the clamping faces, shoulders and abutments not only resulting in the tool or abrasive stick being held firmly in fixed position, but the liability of fracture of the abrasive stick, present in other types of holder, is avoided.

Nor is the truing device as a whole limited to the details of construction herein shown and described, as the form and arrangement of the various parts may be modified and varied without departing from the invention as set forth in the appended claims.

Having thus described the invention, what is claimed is:

1. A truing device for polishing wheels and the like comprising a guideway, a carriage on said guideway, means for moving the carriage on the guideway, and a tool holder on the carriage, the holder comprising an abutment member and a co-operating clamping member for supporting therebetween the truing tool, the abutment and clamping members each having tool engaging-faces at right angles to one another, the faces on one member being opposite the faces on the other member whereby the tool is clamped between opposite pairs of clamping faces.

2. A tool holder for polishing machines and the like, comprising an abutment member having a plurality of clamping faces and a threaded opening, a clamping member having a plurality of clamping faces and a stop for engaging the abutment member, and a bolt passing through the clamping member between the clamping faces on one side and the stop on the other and entering the threaded opening for clamping a tool in position between the abutment and the clamping members, the stop on the clamping member preventing tilting of said member.

3. A tool holder for polishing machines and the like, comprising an abutment member, a clamping member having a plurality of spaced clamping faces, means laterally disposed with respect to the clamping faces for forcing the members toward one another to clamp a tool therebetween, one of said members having provision for maintaining the members in proper angular relation.

4. In a polishing machine or the like, the com-

bination with a rotating wheel, a casing enclosing the wheel and provided with a clamping abutment and lug at the top and an opening for the presentation of the work in the front thereof, a truing device comprising an arm pivoted on the lug on an axis parallel to the axis of the wheel and having a clamping face for engagement with the abutment when the truing device is swung forwardly on its pivotal support, and a truing tool mounted on the arm, the tool being projected through the opening to engage the face of the wheel when the device is swung forwardly, the device being adapted to be swung rearwardly to rest upon the casing in inoperative position distant from said opening, and means for clamping the face on the arm in engagement with the abutment on the casing to hold the truing device in fixed operative position.

5 20 5. In a polishing machine or the like, the combination with a rotating wheel, of a circular casing enclosing the wheel and provided with a peripheral opening for the presentation of the work to the wheel, a truing device comprising an arm pivotally mounted at one end on the

casing on an axis parallel to the axis of rotation of the wheel and a truing tool mounted at the other end of the arm, the pivot of the arm being positioned on the periphery of the casing to permit movement of the arm in the plane of rotation of the wheel to cause the tool to extend through the opening in the casing to engage the face of the wheel when the arm is swung forwardly into operative position, and to rest upon the periphery of the casing in the rear 10 of the pivot when the arm is swung rearwardly into inoperative position, an abutment on the periphery of the casing provided with a screw projecting upwardly therefrom, a cooperating abutment on the arm provided with an internally threaded rotatable sleeve adapted to be brought into engagement with the screw when the arm is swung forwardly, and means for rotating the sleeve while in engagement with the screw to draw the arm into operative position 15 and said abutments into clamping engagement, thereby to position and fixedly secure the arm with relation to the wheel.
